[57] CLAIM

The ornamental design for an tetrahedral top carton, as shown and described.

DESCRIPTION

FIG. 1 is a top perspective view of a tetrahedral top carton; FIG. 2 is a front elevational view of the tetrahedral top carton shown in FIG. 1;

FIG. 3 is a side elevational view of the tetrahedral top carton shown in FIG. 1, the opposite side being a mirror image; and,

FIG. 4 is a top plan view of the tetrahedral top carton shown in FIG. 1.

The undisclosed rear view of the tetrahedral top carton forms no part of the claimed design.
